[57] CLAIM

The ornamental design for a nursing sling, as shown and described.

DESCRIPTION

FIG. 1 is a front elevational view of the nursing sling of the present invention;

FIG. 2 is a back elevational view of the nursing sling of FIG. 1;

FIG. 3 is a left side elevational view of the nursing sling of FIG. 1;

FIG. 4 is a right side elevational view of the nursing sling of FIG. 1;

FIG. 5 is a top plan view of the nursing sling of FIG. 1;

FIG. 6 is a bottom plan view of the nursing sling of FIG. 1;

FIG. 7 is a front elevational view of the nursing sling of FIG. 1 folded for use; and,

FIG. 8 is a front elevational view of the nursing sling of FIG. 1 in unfolded condition; the broken line showing being for illustrative purposes only and forming no part of the claimed design.
